[57] CLAIM

The ornamental design for a light reflector for photographic light, as shown and described.

DESCRIPTION

FIG. 1 is a perspective view of a light reflector for photographic light showing my new design;

FIG. 2 is a front elevational view thereof on an enlarged scale;

FIG. 3 is a side elevational view thereof on an enlarged scale, the opposite side being a mirror image;

FIG. 4 is a rear elevational view thereof on an enlarged scale.

FIG.1.

FIG.2.
